CLAIM

The ornamental design for a combustion gas analyzer
for measuring temperature, smoke density and CO₂ of
flue gas of an oil or gas burner, as shown and described.

DESCRIPTION

FIG. 1 is a perspective view of a combustion gas analyzer
for measuring temperature, smoke density and CO₂
of flue gas of an oil or gas burner showing my new
design

FIG. 2 is a front elevational view thereof;

FIG. 3 is a side elevational view from one side;

FIG. 4 is a top plan view;

FIG. 5 is a side elevational view from the other side;

FIG. 6 is a bottom view and

FIG. 7 is a rear elevational view thereof.
